VALVE VIBRATOR AND HEATER

Rex De Ore McDill, Cleveland, Ohio, assignor to
Thompson Products, Inc., a corporation of
Ohio

Application June 21, 1943, Serial No. 491,665

5 Claims. (Cl. 259—72)

This invention relates to a valve vibrator and heater and more particularly to a method and means for causing the sodium contained within a hollow valve to be moved to a desired location in the valve cavity with the free surface of the sodium disposed at a predetermined angle with respect to the longitudinal axis of the valve stem.

Under certain circumstances it has been found desirable and necessary to move all of the sodium within a hollow partially filled valve to some desired location therein, such, for example, as when the valve is to be tested for its sodium content or when the thickness of various portions of the valve wall is to be measured.

One of the principal objects and features of the present invention is to provide a novel method and means for moving the sodium to some definite position within a valve and to definitely determine the angle which the free surface of the sodium within the valve makes with respect to the longitudinal axis of the valve stem.

Another object of the present invention is to provide a novel valve vibrator and heater.

A further object of the present invention is to provide novel equipment for simultaneously heating a sodium filled valve and vibrating the same.

The novel features which I believe to be characteristic of my invention are set forth with particularity in the appended claims. My invention itself, however, both as to its manner of construction and method, together with further objects and advantages thereof, may best be understood by reference to the following description, taken in connection with the accompanying drawings, in which:

Figure 1 is a plan view of a valve vibrator and heater which embodies novel features of the present invention;

Figure 2 is an enlarged fragmentary plan view of a portion of the apparatus shown in Figure 1;

Figure 3 is a vertical sectional view of the valve vibrator and heater taken along the line III—III of Figure 2;

Figure 4 is a front elevational view of the valve vibrator and heater shown in Figure 1 after it has been elevated by its legs so as to be disposed at a predetermined angle with respect to the horizontal;

Figure 5 is a fragmentary plan view showing a modified form of the present invention; and

Figure 6 is a vertical sectional view as taken along the line VI—VI of Figure 5.

Referring now to the embodiment of the invention which is illustrated in Figures 1 to 4 of the drawings, a casing 10 is provided which is gen-

erally in the form of a rectangular box having side and end walls 11 which are lined with sheets of insulating material 12, such as asbestos, and a bottom wall 13. The top of the housing 10 is open and a plurality of valves 14 may be freely suspended therethrough.

A plurality of electric heating units 15 are mounted in the bottom of the housing 10 and the heating elements 16 thereof are arranged to 10 heat the heads 17 of the valves 14 which are mounted directly thereover.

I have found in practice that when a sodium filled valve is simultaneously heated and vibrated that substantially all of the sodium within the 15 valve will be moved to the bottom of the cavity as determined by the position in which the valve is suspended, with the free surface of the sodium lying in a horizontal plane. It will thus be apparent to those skilled in the art that by simultaneously heating and vibrating the valve with the valve stem held in a predetermined position with respect to the horizontal that the sodium within the valve may be moved so that its free 20 surface is disposed at the same angle with respect 25 to the valve stem axis as the valve stem axis is with respect to the horizontal.

Having described the heating chamber by which the valves are heated, I will now describe the mechanism for vibrating and supporting the 30 valves.

In the form of the invention shown in Figures 1 to 4 of the drawings, a plurality of valve supporting bars 18 extend across the top of the housing 10. Each bar 18 is supported at one end 35 on an adjustable bolt 19 which is threaded into the top flange 20 of the housing 10. An intermediate portion of each bar 18 is supported on a helical spring 21 which is carried on a bracket 22 mounted on a sub-base 23 which in turn is supported by brackets 24 on one of the side walls 11 of the housing 10. The spring 21 is held in place by four guide pins 25.

Each bar 18 is also provided with an aperture 26 through which a guide pin 27, carried on the 40 top flange 20 of the housing 10, extends. Secured to the under side of each bar 18 directly over the top of the housing 10 is a composite member 29 formed of two sheets of metal 30 and 31 with a sheet of heat insulating material 32 such as 45 asbestos disposed therebetween. This composite unit 29 is bolted or otherwise suitably secured to the bar 18 such as by means of bolts 33. The sheets 30, 31 and 32 are all bolted together by means of bolts 34. The end of the composite member 29 remote from the spring 21 is pro-

vided with a cut-out portion 35 so as not to interfere with the support of the bar 18 on the bolt 19 and to permit a pair of guide pins 36 to extend up past either side of the bar 18 to prevent lateral movement of the same off of bolt 19. The members 29 limit rocking movement of the bars 18 about their own longitudinal axis. Such movement may be further restricted by interconnecting adjacent bars 18 by a cross-tie 61.

Mounted on the sub-base 23 are a plurality of solenoids 37 each having a three-legged laminated iron core 38. The compression springs 21 normally hold each of the bars 18 slightly above the upper surface of the laminated iron core 38. Each of the solenoids 37 is arranged to be energized from a transformer 39 which in turn is preferably connected to a source of alternating current such as the usual 110 volt 60 cycle alternating current provided by public utility companies throughout the country. When the solenoids 37 are energized by 60 cycle alternating current the bars 18 are vibrated 60 times a second about their supports 19.

The valves 14 are suspended from the bars 18 by providing each bar with a pair of bushings 40 through which the valve stem 41 extends. The upper end of the valve stem 41 which protrudes through the bushing 40 is engaged by a collar 42 having a set screw 43 which may be tightened against the valve stem. When the valves 14 are suspended in the manner as shown in Figure 3 of the drawings, heated by the heating element 15, and vibrated by the solenoid 37, the sodium within the valves 14 is all deposited within the valve head with the upper surface of the sodium disposed in a horizontal plane, or in other words, at right angles to the longitudinal axis of the valve stem. It is frequently desirable that the upper surface of the sodium be disposed in a plane lying at an angle to the longitudinal axis of the valve stem, such, for example, as at an angle of 45°. This is accomplished by providing the unit shown in Figures 1 to 3 of the drawings with a pair of legs 44 each having a slot 45 therein through which a wing bolt 46 extends and engages the side wall of the housing 10. When the unit is disposed at a 45° angle with respect to the horizontal, and the valves are vibrated in that position, it will be apparent that all of the sodium within the valves will be moved into one corner of the valve cavity with the free surface of the sodium disposed at a 45° angle with respect to the axis of the valve stem.

In Figures 5 and 6 of the drawings, a modification of the present invention is illustrated which provides means for bumping the sodium into the skirt and stem of the valve. More specifically, a heating chamber is provided by a housing 47 having a plurality of heating elements 48 mounted in the base thereof. The heating chamber is provided with a plurality of apertures 49 in the base wall 50 thereof through which the stems 41 of the valves 14 extend. A plurality of bars 51 are mounted below the base wall 50 directly under the apertures 49. Each bar 51 is supported in a bracket 52 on one side of the heating chamber 47. The opposite end of the bar 51 extends over a solenoid 53 having a laminated iron core 54. An intermediate portion of the bar 51 is supported by a compression spring 55 carried on a bracket 56 and held in place by a plurality of guide pins 57.

The solenoids 53 are energized in a manner similar to that described in connection with the preferred embodiment of the invention and cause

the bars 51 to be vibrated. Collars 58 are secured to the bars 51 in any suitable manner and are provided with set screws 59 for clamping the ends of the valve stems 41 within the collars 59.

5 The above described structure is all mounted on a suitable frame 60 which may be of any suitable form and shape.

10 While I have shown and described certain particular embodiments of my invention, it will, of course, be understood that I do not wish to be limited thereto since many modifications may be made, and I therefore contemplate, by the appended claims, to cover all such modifications as fall within the true spirit and scope of my invention.

15 I claim as my invention:

20 1. A valve vibrator and heater comprising a heating chamber having an opening in the upper portion thereof, a valve suspension member extending across and above the opening, said suspension member being supported for pivotal movement in one side of said opening and having electromagnetic means for vibrating said suspension member in proximity to the other side 25 of said opening, and means intermediate said pivotal support and said vibrating means for suspending a valve within said chamber.

25 2. A valve vibrator and heater comprising a heating chamber having an opening in the upper portion thereof, a valve suspension member extending completely across and above the opening, one end of said suspension member extending beyond one of the outer edges of said heating chamber, said suspension member having its other end supported for pivotal movement and for proximity to one side of said opening, electromagnetic means for vibrating said one end which extends beyond said heating chamber, and means intermediate said pivotal support and said vibrating means for suspending a valve within said chamber.

30 3. A valve vibrator and heater comprising a heating chamber, a valve suspension member extending across said chamber, means for supporting said suspension member at one side of said chamber for limited angular movement, means at the other side of said chamber for confining said angular movement to movement toward and away from the interior of said chamber, electromagnetic means in proximity to said movement confining means for vibrating said member, and means intermediate said supporting means and said movement confining means for suspending a valve within said chamber.

35 4. A valve vibrator and heater comprising a heating chamber, a valve suspension member extending across said chamber, means for supporting said suspension member at one side of said chamber for limited angular movement, means at the other side of said chamber for confining said angular movement to movement toward and away from the interior of said chamber, said suspension member extending a substantial distance beyond the side of said chamber in which said movement confining means is located, resilient means in proximity to said movement confining means for resiliently supporting said suspension member and electromagnetic means for vibrating the end of said suspension member which extends beyond said heating chamber.

40 5. A valve vibrator and heater comprising a heating chamber, a valve suspension member extending across said chamber, means for supporting said suspension member at one side of said chamber for limited angular movement, means

at the other side of said chamber for confining said angular movement to movement toward and away from the interior of said chamber, said suspension member extending a substantial distance beyond the side of said chamber in which said movement confining means is located, resilient means in proximity to said movement confining means for resiliently supporting said sus-

pension member and electromagnetic means for vibrating the end of said suspension member which extends beyond said heating chamber, said resilient means being disposed between said heating chamber and said electromagnetic vibrating means.

REX DE ORE McDILL.
